US00D981345S

(12) **United States Design Patent** (10) Patent No.: **US D981,345 S**
(45) Date of Patent: **** Mar. 21, 2023**

(54)	SHAPED CHARGE CASING	2,889,775 A	6/1959	Owen
(71)	Applicant: DynaEnergetics Europe GmbH , Troisdorf (DE)	2,946,283 A	7/1960	Udry
(72)	Inventors: Christian Eitschberger , Munich (DE); Thilo Scharf , Letterkenny (IE)	3,019,731 A	2/1962	David et al.
(73)	Assignee: DynaEnergetics Europe GmbH , Troisdorf (DE)	3,077,834 A	2/1963	Caldwell
(**)	Term: 15 Years	3,119,178 A	1/1964	Owen et al.
(21)	Appl. No.: 29/758,155	3,170,400 A	2/1965	Nelson
(22)	Filed: Nov. 12, 2020	3,246,707 A	4/1966	Bell
	Related U.S. Application Data	3,255,659 A	6/1966	Venghiattis
(63)	Continuation-in-part of application No. PCT/EP2020/058241, filed on Mar. 24, 2020.	3,327,630 A	6/1967	Bell
(51)	LOC (14) Cl. 13-02	3,374,735 A	3/1968	Moore
(52)	U.S. Cl. USPC ..... D13/118 ; D22/199; D13/151	3,375,108 A	3/1968	Wyman et al.
(58)	Field of Classification Search USPC ..... D13/101, 110, 118, 151, 184, 199; D15/138, 139; D9/500, 502, 505; D22/108, 109, 110, 111, 112; D23/259, D23/262, 266 CPC G01V 1/08; G01V 1/104; E21B 43/11; E21B 43/116; E21B 43/117; E21B 43/119; E21B 43/1185; E21B 47/12; F24B 1/032	4,044,810 A	5/1969	Hakala
	See application file for complete search history.	3,504,723 A	4/1970	Cushman et al.
(56)	References Cited	3,565,188 A	2/1971	Hakala

(57) **CLAIM**

We claim the ornamental design of a shaped charge casing, as shown and described.

DESCRIPTION

FIG. 1 is a front, top perspective view of a shaped charge casing showing our new design;

FIG. 2 is a front, bottom perspective view of the shaped charge casing of FIG. 1;

FIG. 3 is a front elevated view of the shaped charge casing of FIG. 1;

FIG. 4 is a rear elevated view of the shaped charge casing of FIG. 1;

FIG. 5 is a left-side elevated view of the shaped charge casing of FIG. 1;

FIG. 6 is a right-side elevated view of the shaped charge casing of FIG. 1;

FIG. 7 is a top plan view of the shaped charge casing of FIG. 1;

FIG. 8 is a bottom plan view of the shaped charge casing of FIG. 1; and,

FIG. 9 is a cross-section view of the shaped charge casing taken along line 9-9 of FIG. 7.

The broken lines consisting of a double-dot/dash pattern define the bounds of the claimed design and form no part thereof.
